US00D926233S

(12) **United States Design Patent** (10) **Patent No.:** **US D926,233 S**
(45) **Date of Patent:** **** Jul. 27, 2021**

(54) **CALIBRATION BATH**

(71) Applicant: **Fluke Corporation**, Everett, WA (US)

(72) Inventors: **David W. Farley**, Orem, UT (US);
Matthew B. Marzynski, Seattle, WA
(US)

(73) Assignee: **Fluke Corporation**, Everett, WA (US)

(**) Term: **15 Years**

(21) Appl. No.: **29/703,119**

(22) Filed: **Aug. 23, 2019**

Related U.S. Application Data

(62) Division of application No. 29/592,987, filed on Feb. 3, 2017, now Pat. No. Des. 862,527.

(57) **CLAIM**

The ornamental design for a calibration bath, as shown and described.

DESCRIPTION

FIG. 1 is a top front right perspective view of a calibration bath showing our new design.

FIG. 2 is a bottom rear left perspective view thereof.

FIG. 3 is a front elevation view thereof.

FIG. 4 is a right side elevation view thereof.

FIG. 5 is a left side elevation view thereof.

FIG. 6 is a top plan view thereof.

FIG. 7 is a rear elevation view thereof.

FIG. 8 is a bottom plan view thereof.

FIG. 9 is a top front right perspective view of another embodiment of a calibration bath showing our new design.

FIG. 10 is a bottom rear left perspective view thereof.

FIG. 11 is a front elevation view thereof.

FIG. 12 is a right side elevation view thereof.

FIG. 13 is a left side elevation view thereof.

FIG. 14 is a top plan view thereof.

FIG. 15 is a rear elevation view thereof; and,

FIG. 16 is a bottom plan view thereof.

The broken lines in the figures illustrate environment and/or aspects of the calibration bath that form no part of the claimed design.

1 Claim, 16 Drawing Sheets
